UNITED STATES PATENT OFFICE.

JOHN F. NORMAN, OF LIMA, OHIO, ASSIGNOR OF ONE-HALF TO CHARLES ERSHICK, OF LIMA, OHIO.

APPLIANCE FOR BREAKING METAL NUTS.

1,102,162.

Specification of Letters Patent. Patented June 30, 1914.

Application filed July 22, 1913. Serial No. 780,586.

To all whom it may concern:

Be it known that I, JOHN F. NORMAN, a citizen of the United States, residing at Lima, in the county of Allen and State of Ohio, have invented new and useful Improvements in Appliances for Breaking Metal Nuts, of which the following is a specification.

This invention relates to appliances for breaking metal nuts which are not readily removable from their bolts, such a device having general utility in various environments, being especially useful in the repair of freight cars.

15 The object of the invention is to provide a device for the purpose stated having means whereby the breakage of the nut and its consequent removal from the bolt may be accomplished quickly and with facility, and 20 having its parts constructed to accommodate nuts of varying shapes and sizes.

The improved appliance is simple in its structural details and is of substantial nature, whereby it will not be detrimentally 25 affected by rough usage.

An embodiment of the invention is illustrated in the accompanying drawings, wherein:

Figure 1 is a perspective view of the appliance; Fig. 2 is a vertical cross sectional view thereof; Fig. 3 is a vertical longitudinal sectional view thereof; and Fig. 4 is a horizontal sectional view on the line 4—4 of Fig. 3, looking in the direction of the arrow.

35 Similar characters of reference designate corresponding parts throughout the several views.

The nut to be broken is supported upon a relatively heavy anvil 1, preferably in the 40 form of an upright oblong block and having at one side thereof a handle 2 by means of which the appliance may be readily carried in the hand. The breaking of the nut is accomplished by a cutter or chisel 3 and the 45 nut is centered with relation to said cutter or chisel by a pair of jaws 4 associated with the upper face of the anvil 1.

A bracket 5 is secured to the anvil 1 and projects upwardly therefrom, this bracket 50 being provided with horizontal webs 6 having openings through which the chisel 3 is movable, and which, of course, guide said chisel in its movements. The chisel 3 is held in a normal relation by an expansive coil 55 spring 7 which is arranged between the webs

6. The spring 7 is preferably of tapering form and is secured at its center, as by a cotter pin 8, to the chisel, a coil of the spring passing through the eye of said cotter pin.

The bracket 5 includes a pair of cheeks 9 which lie adjacent the sides of the anvil 1 and are secured thereto. The cheeks 9 are provided with longitudinal slots 10 and a bolt 11 passes through a transverse opening in the anvil and through the slots 10, the bolt 11 being provided with a head at one end and a wing nut 12 at the other end. The cheeks 9 are clamped against the sides of the anvil by tightening the nut 12, as is obvious, and in order that the bracket 5 may be positively held against movement relative to said anvil, the inner faces of the cheeks 9 and the adjacent faces of the anvil are provided with mating corrugations 13. The cheeks 9 have a certain measure of resiliency, and tend to 70 spring away from the sides of the anvil, and it follows that when the nut 12 is turned to relieve the clamping pressure on the cheeks, the latter disengage the corrugated sides of the anvil, thereby enabling the bracket 5 to 75 be adjusted vertically with relation to the anvil, such adjustment being provided for by the slots 10.

The vertical adjustment of the bracket 5 relative to the anvil is made in view of the 85 diameter of the nut to be broken, in order that, as the diameter of the nut may be greater or less, the cutting edge of the chisel 3 may have a normally greater or less spacing from the upper face of the anvil, the 90 normal position of the chisel relative to the anvil therefore being selected to conform to the diameter of the nut. The position of the jaws 4 relative to one another may also be varied in accordance with the diameter of 95 the nut. The means for adjusting the jaws 4 preferably comprises a right and left threaded screw 14 which passes through a dovetail recess 15 formed transversely in the upper face of the anvil and through the slots 10 in the cheeks 9, and lugs 16 formed as parts of the jaws 4 and which are engaged with the respective right and left threads of the screw 14. The lugs 16 are of dovetail outline and fit conformably in the recess 15. 100 To prevent the screw 14 from having any play which might interfere with the accuracy of the adjustment of the jaws 4, a wing nut 17 is secured on one end of said screw, as by a cotter pin and an expansive coil 110

spring 18 bears between said wing nut and the face of the adjacent cheek 9, the other end of the screw being headed or otherwise constructed to bear against the other cheek 9.

In order that the operation of the chisel 3 may be facilitated, said chisel is arranged on an axis which is slightly inclined relatively to the perpendicular, so that the chisel, in breaking the nut, has a shearing action.

To enable the nut to spread consequent to the action of the chisel 3, the jaws 4, by which the nut is centered, diverge as they approach the front of the anvil.

In use, the nut is positioned between the jaws 4 and as far toward the rear side of the anvil as the relation of said jaws will permit. In such position the nut is centered relatively to the chisel 3 and the latter is given a sharp blow with a hammer, whereby it is driven downwardly and cuts or splits the nut, the chisel having a shearing action on the nut, owing to its inclination relative to the perpendicular. The spring 7 returns the chisel to normal position, the upper portion of said spring cushioning the rebound, as is obvious.

The bracket 5 may be quickly and conveniently removed from the anvil 1 whenever the occasion may require. With this object in view, one of the slots 10 extends to the lower edge of the cheek 9 and the heads of the bolt 11 and screw 13 are located adjacent this open slot. When the bracket is to be removed, the wing nuts are taken from the other ends of the bolt 11 and screw 14 and said bolt and screw are moved laterally until their unheaded ends pass from the adjacent slots 10. Thereupon the bracket may be lifted vertically from the anvil 1, as is obvious. While both of the slots 10 could be made with open lower ends, it is preferable to have but one of said slots so made, in order to eliminate any possibility of the accidental separation of the bracket 5 and anvil 1.

Having fully described my invention, I claim:

1. An appliance for breaking metal nuts, comprising an anvil, a bracket upright therefrom, means for adjusting the elevation of the bracket relatively to the anvil, a pair of nut centering jaws associated with the upper face of the anvil, means for adjusting said jaws relatively to one another, and a spring held chisel carried by the bracket.

2. An appliance for breaking metal nuts, comprising an anvil, a bracket upright therefrom, nut centering jaws associated with the upper face of the anvil, and a chisel carried by the bracket and movable along its axis, the axis of the chisel being inclined relatively to the perpendicular, whereby

the chisel has a shearing action in its cutting operation.

3. An appliance for breaking metal nuts, comprising an anvil, a bracket upright therefrom, a pair of nut centering jaws associated with the upper face of the anvil and having a diverging relation, and a chisel carried by the bracket and movable along its axis, the axis of the chisel being inclined relatively to the perpendicular and being directed downwardly toward that face of the anvil toward which said centering jaws diverge, the chisel having a shearing action in its cutting operation.

4. An appliance for breaking metal nuts, comprising an anvil, a bracket upright therefrom and having a pair of cheeks which are held adjacent the side faces of the anvil and are provided with longitudinal slots, the adjacent faces of the cheeks and the anvil having mating corrugations, a bolt passing through the anvil and through said slots and having a clamping nut at one end thereof to hold the cheeks in locked relation to the anvil, nut centering jaws associated with the upper face of the anvil, and a spring-held cutter carried by the bracket.

5. An appliance for breaking metal nuts, comprising an anvil, a bracket upright therefrom and having a pair of cheeks which are held adjacent the side faces of the anvil and are provided with longitudinal slots, a bolt passing through the anvil and through said slots and having a clamping nut at one end thereof to hold the cheeks in locked relation to the anvil, nut centering jaws associated with the upper face of the anvil, and a spring held cutter carried by the bracket.

6. An appliance for breaking metal nuts, comprising an anvil, a bracket upright therefrom and having a pair of cheeks which are held adjacent the side faces of the anvil and are provided with longitudinal slots, one of which extends to the lower edge of the cheek in which it is formed, the adjacent faces of the cheeks and the anvil having mating corrugations, a bolt passing through the anvil and through said slots and having a clamping nut at one end thereof to hold the cheeks in locked relation to the anvil, nut centering jaws associated with the upper face of the anvil, and a spring held cutter carried by the bracket.

7. An appliance for breaking metal nuts, comprising an anvil, a bracket upright therefrom, a pair of cutting jaws associated with the upper face of the anvil, the anvil having a transverse groove in its upper face and the jaws having lugs which engage in said groove, a right and left threaded screw disposed in the groove and having its oppositely directed threads engaged with said respective lugs, a coil spring acting on one

end of the screw to take up loose play, and a chisel carried by the bracket.

8. An appliance for breaking metal nuts, comprising an anvil, a bracket upright

5 therefrom and having a pair of cheeks which are held adjacent the side faces of the anvil and are provided with longitudinal slots, a bolt passing through the anvil and through said slots and having a clamping nut at one 10 end thereof to hold the cheeks in locked relation to the anvil, a pair of centering jaws associated with the upper face of the anvil, the anvil having a transverse groove in its upper face and the jaws having lugs which 15 engage in said groove, a right and left threaded screw disposed in the groove and having its oppositely directed threads engaged with said respective lugs, the ends of the screw projecting through the slots, a coil 20 spring acting on one end of the screw to take up loose play, and a chisel carried by the bracket.

9. An appliance for breaking metal nuts, comprising an anvil, a bracket upright 25 therefrom, means for adjusting the elevation of the bracket relatively to the anvil, a pair of nut centering jaws associated with the upper face of the anvil, means for adjusting said jaws relatively to one another, and a 30 chisel carried by the bracket.

10. An appliance for breaking metal nuts, comprising an anvil, a bracket upright therefrom, a pair of nut centering jaws associated with the upper face of the anvil and 35 having a diverging relation, a chisel carried by the bracket and movable along its axis,

the axis of the chisel being inclined relatively to the perpendicular, and means for adjusting said jaws relatively to one another.

40

11. An appliance for breaking metal nuts, comprising an anvil, a bracket upright therefrom, a pair of nut centering jaws associated with the upper face of the anvil and having a diverging relation, a chisel carried 45 by the bracket and movable along its axis, the axis of the chisel being inclined relatively to the perpendicular, means for adjusting said jaws relatively to one another, and means for adjusting the elevation of the 50 bracket relatively to the anvil.

12. An appliance for breaking metal nuts, comprising an anvil, a bracket upright therefrom and having a pair of cheeks which are held adjacent the side faces of the 55 anvil and are provided with longitudinal slots, one of which extends to the lower edge of the cheek in which it is formed, a bolt passing through the anvil and through said slots and having a clamping nut at one end 60 thereof to hold the cheeks in locked relation to the anvil, nut centering jaws associated with the upper face of the anvil, and a spring held cutter carried by the bracket.

In testimony whereof I have hereunto set 65 my hand in presence of two subscribing witnesses.

JOHN F. NORMAN.
